UNITED STATES PATENT OFFICE.

LEWIS C. MALTBY, OF WASHINGTON, DISTRICT OF COLUMBIA, ASSIGNOR TO THE STONE STRAW COMPANY, OF WASHINGTON, DISTRICT OF COLUMBIA, A CORPORATION OF NEW JERSEY.

MACHINE FOR MANUFACTURING SPIRALLY-WOUND STRAWS.

1,252,284.

Specification of Letters Patent.

Patented Jan. 1, 1918.

Application filed February 12, 1916. Serial No. 78,056.

To all whom it may concern:

Be it known that I, LEWIS C. MALTBY, a citizen of the United States, residing at Washington, in the District of Columbia, 5 have invented certain new and useful Improvements in Machines for Manufacturing Spirally-Wound Straws, of which the following is a specification.

My invention relates to an improvement 10 in machines for manufacturing spirally-wound straws.

One of the fundamental features of this invention is the construction and arrangement of parts whereby the glue-pot is brought 15 into close proximity and intimate relation with the point on the mandrel where the winding or spinning takes place, so that the distance for the paper to travel after it leaves the glue-wheel to the mandrel is reduced to a minimum, which is an important 20 consideration where a quick-setting glue is used, as is the case in this art, and where it is important that there should be just as little play and vibration of the paper strips 25 as possible in reaching the mandrel.

Another important feature is my present arrangement for adjusting the tension of the belt without changing its angle, all of which and other features will be hereinafter more 30 fully described in the specification and recited in the claims.

In the accompanying drawings:—

Figure 1 is a plan view;

Fig. 2 is a view in side elevation;

Fig. 3 is an end view of the cut-off mechanism;

Fig. 4 is a section on line 4—4 of Fig. 1, looking to the right or in the direction of the arrow;

Fig. 5 is a similar section on line 5—5 of Fig. 1, looking toward the right, as indicated by the arrow;

Fig. 6 is a section on the line 6—6 of Fig. 1, looking toward the left;

Fig. 7 is a longitudinal vertical section of a form of tension device employed with this machine;

Fig. 8 is a plan view of the tension device;

Fig. 9 is an end view.

Fig. A, represents the bed or frame of the machine, mounted as usual on legs or other supports 1, which are partially shown in Figs. 3 and 4.

Across this bed, a bolster B extends diag-

onally at the required angle, as shown in 55 Fig. 1. This bolster has a hub 2 at the center, which fits and is capable of turning in the central orifice 3 of the bed.

The bolster forms the support for the entire straw-winding or spinning mechanism 60 with the exception of the mandrel 4, which latter is adjustably supported by the bracket 5 bolted to the bed A in a horizontal position, extending lengthwise of the bed, as shown in Figs. 1, 2 and 6.

Cross-heads 6 and 7 are dovetailed to and 65 slidably connected with the beveled edges of the bolster, as shown in Figs. 1, 2 and 6, they being adjusted by the screws 8 and 9, which are swiveled in the lugs 10 and 11 on 70 corresponding sides of the cross-heads, and turn in threaded orifices in the lugs 12 and 13 on the bolster, these screws being turned to the right to force the cross-heads outwardly, and to the left to slide them toward 75 the center.

Mounted on the cross-heads are the yokes 14 and 15, which latter afford bearings 16 and 17 for the vertical shafts 18 and 19, which carry at their upper ends the pulleys 80 20 and 21 respectively, over which the winding or spinning belt 22 is carried.

On the lower ends of these vertical shafts 18 and 19, the bevel-gears 24 and 25 are keyed, and the teeth of these bevel-gears 85 mesh with corresponding gears 26 and 27 respectively keyed on the horizontal shafts 28 and 29, which latter are journaled and supported on the bolster B, as shown in Figs. 1, 2 and 6.

These shafts 28 and 29 have bevel gears 30 and 31 keyed to their inner ends respectively, as shown in Figs. 1 and 6. These bevel-gears 30 and 31 both mesh with, on 90 opposite sides of, a horizontally-disposed gear 32 keyed on the vertical centrally-located shaft 33, which extends down through the hub 2 of the bolster, as shown in Fig. 6, and has a large bevel gear 34 keyed to its lower end. The teeth of this gear mesh with a bevel-gear 35 keyed on the main horizontal drive-shaft 36 supported in bearings 37 longitudinally beneath the bed A, and on the outer end of which the main drive-pulley 38 is secured.

The belt, as is customary, is wound several (preferably three) times around the mandrel, as illustrated in Fig. 1, and its tension

may be regulated at any time without stopping the machine or varying the angle of the belt by simply applying a wrench to one or both of the screws 8 and 9 and turning them to the right or left, accordingly as the belt is to be tightened or loosened, and likewise the angle of the belt may be varied to suit the requirements at any time without interfering with the operation of the machine, by simply shifting the bolster the required degree to the right or left.

The glue-pot is represented by the letter G. This rests diagonally upon the bed, as shown in Figs. 1, 2 and 6, in position to be moved beneath the mandrel, and as close as possible to the spinning point of the straws being made upon the mandrel, which takes place approximately at the intersection of the mandrel and center of the bolster, or immediately above the centrally-located vertical shaft 33, as is shown in Figs. 1 and 6. For this purpose, the forward end 40 of the glue-pot is sloped, as shown in Figs. 1, 2 and 6.

This glue-pot contemplates the use of as high as three strips of paper in the formation of a straw as clearly shown in Figs. 1, 8 and 9. A shaft 41 is journaled in bearings 42 in the top of the glue-pot, and on this shaft is secured the glue-wheel 43, over which the uppermost paper strip 44 is fed to the mandrel, the other two strips 45 and 46 being fed directly to the mandrel. A small gear 47 is secured on the end of shaft 41, and this meshes with the teeth of a gear-wheel 48, the axle 49 of which is adjustably supported in a slot 50, which curves in an arc struck from the axial center of the drive-wheel 51, which latter is keyed on the horizontal shaft 29. The purpose of the curved slot 50 is to adjust the wheel 48 to the right or left, accordingly as the glue-pot is moved forward or backward on the bed and with respect to the spinning point on the mandrel.

In connection with this glue-pot, I have introduced a tension device, as shown in Figs. 1, 2, 6, 7, 8 and 9. This comprises a plate 52, which is preferably hinged to the rear edge of the glue-pot, as at 53, so that it may be swung up out of the way. This plate has as many grooves 54 as there are strips of paper, in the present instance three, to be spun into the tube, as shown in Fig. 8. Spring-tensions 55 bear yieldingly upon the bottom of the grooves 54 or the strips 44, 45 and 46 while feeding through the grooves. This spring-tension 55 is held at one end by a set-screw or similar means 56 on the hub 57, mounted on the cross-pin 58 secured by set-screws 59 in the lugs 60 on the plate 52. Adjusting screws 61, three in number, for adjusting the tension of the spring-tensions 55 are supported by the collars 62 secured to the pin 58, and, by turn-

ing these set-screws 61, the required tension is adjusted for each strip being fed thereunder.

The same adjustable slide 63 for removing the superfluous glue from the glue-wheel 43 is provided as set forth in another application Serial No. 78,055, filed concurrently herewith, it being adjusted by means of the swivel-screw 64 turning in the threaded holes 65, as shown in Fig. 7.

The belt 22 theoretically travels as fast as the surface speed of the drive-pulleys 20 and 21. But I have found in practice that it is necessary to allow the belt to slip somewhat on the mandrel 4. For instance, where the surface feed of the belt on the mandrel is three hundred feet per minute, by the introduction of the tensions 55, we held the paper strip back a trifle, say to two hundred and eighty-six feet per minute, or an actual slip of the belt of fourteen feet per minute more than the feed of the paper strips. This made it necessary to have the surface speed of the glue-wheel 43 the same as the paper. The shafts 18, 19 and 41 are geared two to one, and the diameter of the glue-wheel 43 is just enough less than half the diameter of the belt-pulleys 20 and 21 to cause the surface of the glue-wheel 43 to travel the exact speed required for the paper, all of which is provided by the mechanism I have herein described.

The cut-off mechanism is shown at the right in Figs. 1 and 2, and in detail in Figs. 3, 4, and 5. It comprises a drum 66 which is mounted on the counter-shaft 67 journaled in bearings 68 supported on the bed A, as shown in Figs. 1 and 4. This counter-shaft 67 is driven at the required speed from the main drive-shaft 36, through a chain of gears 69, 70, and 71, the latter secured on the shaft 67, all of which is shown in Figs. 1, 2 and 3. This drum 66 has the peripheral cams 72, as well as an end-cam 83, which are the means respectively for reciprocating the saw-dust 73, its shaft 74, the sleeve 75, and the straw-tube 76 through the medium of the collar 77 secured on the sleeve 75, and the anti-friction roller 78, which works in the circumferential cam-groove 72. The saw is rocked in and out of the path of the straw as in the scraper-machine through the rocking frame 79, pivoted at 80 to the brackets 81, by means of the anti-friction roller 82 operating in the end cam 83 (see Fig. 4), and which mechanism need not be further described.

The disk-saw 73 and its shaft are driven by a belt (not shown) passing over the pulley 84 from the main shaft.

I claim:

1. The combination with a machine-bed or frame, a mandrel, and a belt passed around the latter, of a glue-pot placed between the bed and mandrel and in close

proximity to the windings of the belt on the mandrel, a grooved plate hinged to the glue-pot adapted to receive strips of paper being fed to the mandrel, and adjustable tensions 5 carried by the plate which bear yieldingly toward the bottoms of the grooves.

2. The combination with a machine-bed or frame, a mandrel, and a belt passed around the latter, of a glue-pot placed between 10 the bed and mandrel and in close proximity to the windings of the belt on the mandrel, a glue-wheel rotatably supported in the glue-pot, a grooved plate hinged to the glue-pot adapted to receive strips of paper being fed to the mandrel, adjustable tensions 15 carried by the plate which bear yieldingly toward the bottoms of the grooves, and a slide adjustably connected to the lower surface of said hinged plate for scraping the glue from the glue-wheel.

3. The combination with a machine bed or frame and a mandrel, of a bolster carrying horizontal and vertical shafts, means for driving the latter, pulleys carried by the vertical shafts, a belt passed around said pulleys and mandrel, a gear carried by one of the horizontal shafts, a glue-pot, a glue-wheel a trifle less than half the diameter of the belt pulleys and mounted in said glue-pot, a gear on the glue-wheel shaft, and an intermediate gear between said last-named gear and the gear on the horizontal shaft carried by the bolster.

4. The combination with a machine bed

or frame and a mandrel, of a bolster carrying horizontal and vertical shafts, means for driving the latter, pulleys carried by the vertical shafts, a belt passed around said pulleys and mandrel, a gear carried by one of the horizontal shafts, a glue-pot, 35 a glue-wheel a trifle less than half the diameter of the belt pulleys and mounted in said glue-pot, a gear on the glue-wheel shaft, an intermediate gear between said last-named gear and the gear on the horizontal shaft 40 carried by the bolster, and means for adjusting the position of said intermediate gear in an arc from the center of the gear carried by the horizontal shaft on the bolster.

5. The combination with a machine bed or frame and a mandrel, of a bolster carrying horizontal and vertical shafts, means for driving the latter, pulleys carried by the vertical shafts, a belt passed around 55 said pulleys and mandrel, a gear carried by one of the horizontal shafts, a glue-pot over which strips of paper are fed to the mandrel, a glue-wheel a trifle less than half the diameter of the belt pulleys and mounted 60 in said glue-pot, a gear on the glue-wheel shaft, an intermediate gear between said last-named gear and the gear on the horizontal shaft carried by the bolster, and means for applying tension to the strips of 65 paper fed to the mandrel.

In testimony whereof I affix my signature.
LEWIS C. MALTBY.
